US00D775602S

(12) **United States Design Patent** (10) **Patent No.:** **US D775,602 S**
Lee (45) **Date of Patent:** **** Jan. 3, 2017**

(54) **CELLULAR PHONE**

(71) Applicant: **LG Electronics Inc.**, Seoul (KR)

(72) Inventor: **Boyoung Lee**, Seoul (KR)

(73) Assignee: **LG Electronics Inc.**, Seoul (KR)

(**) Term: **14 Years**

(21) Appl. No.: **29/506,359**

(22) Filed: **Oct. 15, 2014**

(30) **Foreign Application Priority Data**

Apr. 18, 2014 (KR) 30-2014-0019880

(51) **LOC (10) Cl.** **14-03**

(52) **U.S. Cl.**

USPC ..... **D14/138 AB**; D14/345

CLAIM

The ornamental design for a cellular one, as shown and described.

DESCRIPTION

FIG. 1 is a front, right side, perspective view of a cellular phone showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view in an open state thereof;

FIG. 9 is a front view in an open state thereof;

FIG. 10 is a rear view in an open state thereof;

FIG. 11 is a left side view in an open state thereof;

FIG. 12 is a right side view in an open state thereof;

FIG. 13 is a top view in an open state thereof; and,

FIG. 14 is a bottom view in an open state thereof.

The broken lines shown in the figures that are immediately adjacent to the shaded areas and define unshaded regions represent the bounds of the claim. The broken lines form no part of the claimed design.

1 Claim, 8 Drawing Sheets
